UNITED STATES PATENT OFFICE.

DE GRASSE FOWLER AND GEORGE FOWLER, OF WALLINGFORD, CONNECTICUT.

MACHINE FOR PUNCHING METAL.

Specification forming part of Letters Patent No. 12,723, dated April 17, 1855; Reissued August 24, 1869, No. 3,617.

To all whom it may concern:

Be it known that we, DE GRASSE FOWLER and GEORGE FOWLER, both of the town of Wallingford, in the county of New Haven 5 and State of Connecticut, have invented a new and useful Improvement in Machines for Punching Metal, &c.; and we do hereby declare that the following is a full, clear, and exact description of the construction, 10 character, and operation of the same, reference being had to the accompanying drawings which make a part of this specification, in which—

Figure 1 is a perspective view of the whole 15 machine, taken from the front end, showing the movement of the punch, its adjustment, &c. Fig. 2 is a perspective view of the same, taken from the rear end, showing the apparatus for putting the punch in and out 20 of gear, &c. Fig. 3 is a view of a longitudinal section, cut vertically through the center, showing a section of all the essential parts. Fig. 4 is a cross section of the eccentric or crank pin, (seen at B, Fig. 1) 25 with an eccentric circle, or case, around it, to vary the eccentricity of the motion.

Our improvement consists in the peculiar manner of connecting the operation of the two levers to throw the machine out of gear 30 at the precise time when the punch is at its greatest elevation, which is the position for putting in, or taking out, the work.

We make the main frame, or body A, A, &c., of the machine, of cast iron or any 35 other suitable material, in the usual way, substantially, of the form shown in Figs. 1 and 2. We ream the hole for the main shaft, tapering, as shown in section in Fig. 3, so as to receive the main shaft, B, with 40 its several off-sets, as shown in section in Fig. 3. We make this main shaft, B, large at the front end to enable us, by the eccentric journal on its end, (as seen at C, Fig. 3) to give sufficient vertical motion to the 45 punch, (which may be assisted by the eccentric circle, v, Fig. 4); and the other parts smaller, to lessen friction, weight, &c., while it retains sufficient strength to prevent trembling.

50 We make the slide, or gate, D, Figs. 1 and 3, of cast iron or other suitable material, and have it slide in ways, a, and a, in the usual way, as shown in Fig. 1. In the central part of this slide we make an oblong mortise, b, with parallel sides, in which we place

the sliding square block, c, with a round hole to receive the eccentric circle, v, Fig. 4, and eccentric journal, C, Fig. 3, as shown at B, Fig. 1.

We make the sliding block, c, so much 60 shorter than the mortise, as to allow it to have sufficient longitudinal motion to accommodate the eccentricity of the journal, even when enlarged by the eccentric circle, v, while it has no room to move in a vertical 65 direction, so that the motion of the eccentric journal will give a reciprocating motion to the slide, D, which carries the punch, d, Figs. 1, 2, and 3.

To graduate the motion of the punch, so 70 that it may come down, at all times, to the exact point desired, we use thin plates, of different thicknesses, which may be placed over, or under, the block c, and changed at pleasure, as seen at e, and e, Figs. 1, and 3. 75 We inclose this block, plates, &c., with a plate, as indicated, in section, at L, Fig. 3.

We fix the female die, f, in a suitable bed, in the usual way, as seen at E, Figs. 1, 2, and 3. The dies may be changed, or varied, 80 at pleasure, to suit any kind of punching, or forming, of metal plates. The main shaft, B, is supported in bearings at g, and h, Fig. 3.

Back of the bearing, h, we fix a permanent 85 collet, F, which always revolves with the shaft, B. In the front side of this collet, we fix a stud, or projection, as seen at i, Fig. 1, which acts upon the upper end, j, of the lever, k, to throw the wheel out of gear. This lever, k, works on a fulcrum screw, l, Figs. 2 and 3, and is held to its place by a spiral spring, m, when the machine is in gear, while its lower end rests on the clutch lever, n, n, as seen in Fig. 2. 90 And in the back, or rear side, of this collet, F, we fix a stud, or projection, o, Fig. 3, against the side of which the sliding rod, p, strikes, or presses, when the machine is in gear. 95

We place the fly-wheel, G, with the loose socket, q, on the rear part of the shaft, B, so as to be turned freely upon it while the machine is out of gear. And, on this socket, q, we place the crank, H, (when a crank is used). Between this wheel, G, and the crank, H, and loose upon the socket, q, we place the clutch, r, which governs the sliding, or connecting, rod, p, as shown in Figs. 2 and 3. This clutch, r, is moved by the 100 105 110

clutch lever, n, n , by means of pins or projections, working in a groove, at r , Figs. 2 and 3. The clutch lever, n, n , works on a fulcrum pin, s , in an inflexible arm, t , attached to the main bed of the frame, as shown in section in Fig. 3, and is worked by the foot applied to the front end, at I , to put the machine in gear; and this front end, I , is drawn up by the spiral spring, K , Fig. 3, to throw the machine out of gear.

Having made and arranged the several parts of the machine, as before described, we apply the power to the crank, H , (or, a band on the wheel, G , or otherwise,) and 15 revolve the wheel, G , in the direction indicated by the dart, when it will revolve freely on the shaft, B , without moving it; (the clutch, r , being in the position indicated in Fig. 3). The workman then places his foot 20 on the end, I , of the clutch lever, n, n , when the upper end of the lever will force the clutch, r , up against the nave of the wheel, G , as seen in Fig. 2, and the sliding rod, p , will be protruded so as to come against the 25 side of the stud, o , in the collet, F , and thereby revolve the shaft, B , which by means of the eccentric journal, C , Fig. 3, (with the eccentric circle, v , arranged as desired, to increase, or diminish, the eccentricity,) will 30 depress, and elevate the punch, d .

When the lower end of the lever, n, n , is depressed so as to put the machine in gear, the lower end of the lever, k , by the action of the spiral spring, m , Fig. 2, will be drawn 35 over and upon the lever, n, n , so as to rest upon it, as shown in Fig. 2, and thus keep

the machine in gear until the punch has operated on the material to be punched, &c., and has been again elevated to its highest position, when the stud, or projection, i , Fig. 40 1, acting on the upper end of the lever, k , will force the lower end off of the lever, n, n , and the spiral spring K , Fig. 3, will draw up the end, I , of the lever, n, n , and force back the clutch, r , to the position shown in Fig. 3, when the rod, p , will not reach the stud, o , and therefore the machine will be 45 out of gear, the punch resting at its highest elevation, and the lower end of the lever, k , resting against the side of the lever, n, n , 50 as shown in section in Fig. 3.

Should it be desired to keep the machine in gear for a number of operations in succession, the end, I , of the lever, n, n , may be held down by the foot, or any other power, greater than that of the spiral spring, K .

What we claim as our invention, and desire to secure by Letters Patent, is—

The peculiar manner of connecting the 60 operation of the two levers, (n, n , and k ,) to throw the machine out of gear at the time when the punch is at its greatest elevation, when constructed, arranged, and made to operate, substantially, in the manner herein 65 described.

DE GRASSE FOWLER.
GEORGE FOWLER.
